DESIGN FOR A SEAT

Leslie J. Wyville and Clarence G. Carlson, Oakland, Calif., assignors to Doo-Tee Corporation, Oakland, Calif., a corporation of Nevada

Application May 1, 1933. Serial No. 47,964

Term of patent 14 years

To all whom it may concern:

Be it known that we, LESLIE J. WYVILLE and CLARENCE G. CARLSON, citizens of the United States of America, residing at Oakland, in the county of Alameda and State of California, have invented a new, original, and ornamental Design for a Seat, of which the following is a specification, reference being had to the accompanying drawing, forming part thereof.

In the drawing:

We claim:

The ornamental design for a seat, as shown.

LESLIE J. WYVILLE.
CLARENCE G. CARLSON.
